UNITED STATES PATENT OFFICE.

JOHN D. COCHRAN, OF MILFORD, NEW HAMPSHIRE.

IMPROVED CLOTHES-WRINGER.

Specification forming part of Letters Patent No. 35,670, dated June 24, 1862.

To all whom it may concern:

Be it known that I, JOHN D. COCHRAN, of Milford, in the county of Hillsborough and State of New Hampshire, have invented an Improved Clothes-Wringer; and I do hereby declare that the following is a full, clear, and exact description of the same, reference being had to the accompanying drawings, forming a part of this specification, and in which—

Figure 1 represents a front view of my improved wringer; and Fig. 2 represents an end view, looking in the direction of arrow 1, Fig. 1.

In the accompanying drawings, A A represent the main supports of the wringer, securely fastened together by cross-pieces B B. The lower ends of the pieces A A are slotted out, as seen in Fig. 2, and are provided with thumb-screws, one of which is seen in same figure, whereby the wringer can be fastened to the top of a tub or wash box. In the upper ends of the pieces A A is supported and turns the crank-shaft D, to which is fastened a roll, E, whose covering is composed of vulcanized india-rubber.

On top of roll E is supported another roll, F, covered with vulcanized rubber. The journal G of this last roll turns in the upper ends of spring-arms H H, whose lower ends are fastened to the edges of the pieces A A by screws or bolts a a. Adjusting bolts b b pass through pieces A A and the spring-arms H H, whereby the latter are kept in the proper position laterally. A brace-rod, I, is also passed from one bolt b to the other.

In order to provide for giving to roll F a greater or less pressure against the roll E, spiral (or rubber) springs c c should be placed upon the bolts b b and forced against arms H H by means of thumb-nuts d d.

In order to have the arms H H of sufficient strength to operate upon very thick materials, and at the same time to enable the machine to be easily adjusted to operate upon fine fabric, supplemental springs J J are applied to the outer ends of the arms H H, and in such manner that the same bolts and screws which hold the former in place confine the latter also. The supplemental springs J J are so constructed as to press with the greatest force against the arms H H above the adjusting bolts b b.

The rolls are turned in the direction indicated by arrows, whereby it will be seen that owing to the relative position of the rolls the tendency of the top roll while in action is to hug the bottom roll, thus insuring perfect wringing of the clothes.

K is a removable slide, which conducts the water back into the wash tub or box.

What I claim as my invention, and desire to secure by Letters Patent, is—

An improved clothes-wringer the various parts of which are constructed, combined, and arranged to operate in relation to each other substantially as shown and described.

JOHN D. COCHRAN.
